FIG. 1 is a front perspective view of a tool for use in the donning and removal of shoes and socks showing my new design;

FIG. 2 is a top plan view thereof;

FIG. 3 is a bottom plan view thereof;

FIG. 4 is a side elevation view thereof, the opposite side elevation view being a mirror image;

FIG. 5 is a front elevation view thereof; and,

FIG. 6 is a rear elevation view thereof.

The broken line showing of the environmental structure of a person donning socks in FIG. 1 is for illustrative purposes only and forms no part of the claimed design.
